UNITED STATES PATENT OFFICE.

BYRON DENSMORE, OF ROCHESTER, NEW YORK.

IMPROVEMENT IN STEAM-BOILERS.

Specification forming part of Letters Patent No. 39,895, dated September 15, 1863; antedated July 15, 1863.

To all whom it may concern:

Be it known that I, BYRON DENSMORE, of the city of Rochester, in the county of Monroe and State of New York, have invented new and useful Improvements in Steam-Boilers; and I do hereby declare that the following is a full and exact description of the construction and operation of the same, reference being had to the annexed drawings, making a part of this specification, in which—

Figure 1 is a perspective view; Fig. 2, a longitudinal elevation; Fig. 3, a transverse horizontal section, showing the lower tube-head and the fire-grate; and Fig. 4, a transverse horizontal section through the center of the boiler, showing the upper tube-head and the fire-flue and the opening out of the tube cylinder into the upper part of the boiler.

The same letters represent corresponding parts in each of the figures.

This is an upright tubular boiler, the lower portion thereof as high up as to the top of the fire-box is of conical form. From there up it is cylindrical. The height of the conical portion will always be about equal to the diameter of the bottom of the boiler and the diameter of the tube-cylinder A about half the diameter of the bottom of the boiler. The length of tube required to absorb the heat will depend upon the size of the boiler and the size of the tube. For a boiler seven feet diameter at bottom and tubes two inches diameter the tubes should be about five feet long, and for a boiler six feet diameter and tubes the same size they should be about four and a half feet long, and for a boiler eight feet diameter two-inch tubes should be about five and a half feet long, and for a boiler twelve feet diameter at bottom and three-inch tubes the tubes should be eight or eight and a half feet long. The crown-sheet of the fire-box should be enough above the upper tube-head to give room to expand the tubes, never less than one and a half feet and never more than three and a half feet. In a boiler six feet diameter at bottom I put in about one hundred two-inch tubes, in one seven feet diameter about one hundred and forty tubes. A boiler twelve feet diameter at bottom would require about one hundred and sixty three-inch tubes. The tube-cylinder A is set on the angle of the side of the cone and forms the outside shell of

the boiler from b b. The outside plate of the boiler rivets to the cylinder A at b b and the lining of the fire-box at c c. The upper tube-head, instead of filling the cylinder all the way around, is cut on the line 2 2, leaving an open space outside of that line to afford circulation between the tube-cylinder and the upper portion of the boiler.

G is the fire-grate; W, water-space; E, fire-jacket; F, outside jacket; H, smoke-stack; L, water-line; R R, stops between the jackets.

The operation of the boiler is as follows: The heat ascends to the top of the fire-box from the grate, is then thrown down through the inclined tubes; thence up through the flue M, which incloses all of the boiler except a small portion of the lower part around the fire-door.

The object of the outside jacket is to carry the heat that is radiated from the inside jacket into the fire, thus obviating the inconvenience of heating the fire-room, and also saving the heat so radiated. This jacket may be used or not, but when used, instead of admitting the air directly from the outside to the grate cold it is admitted at O, and passes upward on that side of the boiler over the top of the stops R R, between the jackets and down on the other side of the boiler, and is thus heated before entering the fire; or the damper under the fire-door may be removed and the air admitted directly to the grate from the outside. This arrangement of boiler gives a very large amount of heating-surface in the fire-box, most of it inclining over the fire, thus giving a stronger radiation against it than if it was perpendicular, and gives a large, roomy fire-box of the form most favorable for a perfect combustion—that is, the fire box is gradually contracted as it ascends, so that at the top of the tube-cylinder it is only large enough to give the requisite size of flue, which causes at this point, together with the undulations in the current in the upper portion of the fire-box, a perfect mingling of the gases from the coal or wood with the oxygen of the air; also, ample time for a perfect combustion. Another thing gained in this arrangement is a large portion of the heat is absorbed before it strikes the tube-head, and striking the head on the upper side, and there being no sediment or scale accumulat.

ing on the inner side of the head where the heat strikes it, there is no difficulty in preserving said head from injury by the fire, as in the ordinary upright tubular boiler. The cold water is fed into the bottom of the tube-cylinder; hence as the heat passes downward through the tubes, it finds the tubes chilled to a decreasing temperature, as there is nothing to heat the water in the bottom of said cylinder, only what heat gets down through the tubes; hence the heat is taken up closer into the boiler than in any other form of boiler known. Then what there is left of the heat after it passes the tubes is used to keep the boiler warm and prevent the external surface of the boiler from condensing the steam generated by the internal heating-surface.

The jackets are made of sheet-iron, either No. 14 or 16, or even lighter will answer for the outside jacket, or it may be made of tin, which is better on account of the reflection. The section of the tube-cylinder *a* where the water comes on both sides of the plate, the plate is cut out or perforated, so as to give a perfect circulation of the water between the cylinder and the other portion of the bottom part of the boiler.

Y is a man-hole for the purpose of clearing

the lower end of the tube-cylinder; *X*, fire-door. The smoke-stack rests on legs on the top of the boiler.

In case of using bituminous coal or any fuel requiring air admitted to the fire above the grate in order to consume the gases, I use hollow stay-bolts in the fire-box with air-passages through the center of the bolts.

I do not claim diving flues in steam-boilers, either standing perpendicularly or on an incline; but

I claim—

1. The tube-cylinder *A*, when attached to the side of the fire-box with the tubes therein standing either perpendicularly or inclined, the fire passing up over said cylinder, then down through the tubes, as described.

2. The arrangement of the fire-box and grate, in combination with the tube-cylinder, as described.

3. The outside jacket, in combination with the stops *R R* and the inside jacket, *E*, for the purposes set forth, as described.

BYRON DENSMORE.
